UNITED STATES PATENT OFFICE.

PETER DE GUERRE, OF TORONTO, ONTARIO, CANADA.

BASE-PLATE FOR A RAIL-CHAIR.

SPECIFICATION forming part of Letters Patent No. 338,589, dated March 23, 1886.

Application filed January 16, 1886. Serial No. 188,750. (No model.) Patented in Canada December 22, 1885, No. 23,040.

To all whom it may concern:

Be it known that I, PETER DE GUERRE, of the city of Toronto, in the county of York, in the Province of Ontario, Canada, yeoman, have 5 invented an Improvement on the Base-Plate of Railway-Rail Chairs; and I do declare that the following is a full, clear, and exact description of the same.

The object of my invention is to secure rail-chairs to their set place upon the rail-tie and to prevent the outward spreading of the chair and rail at the time of extreme pressure, and thus to prevent accidents on railroads from this cause, and consequent loss to railway companies. This object I attain in form illustrated 15 in the accompanying drawings, in which—

Figure 1 is a seat view of the base-plate of a rail-chair, showing ribs and legs on the bottom side. Fig. 2 is a side view showing the 20 ribs and legs projecting downward.

a is the base-plate of a rail-chair.

B B are ribs on the under side of the plate directly under the rail place. (Indicated by dotted lines in Fig. 1.) The ribs *B* are one and 25 one-fourth inch by one and one-fourth inch,

five inches long, and hollow about half-way up. They strengthen the base-plate and are a secure stay, being let into the rail-tie underneath. They are round at the ends, that their place in the tie may be quickly made.

b b are legs, one and one-quarter inch in diameter and the same in length, to be let into the rail-tie, and are hollow about half-way up. They assist each other and the ribs *B* in keeping firm the united power of combination, and thus secure safety from the disastrous results 35 of rail-spreading.

I make no claim to the base-plate as such only, for I am aware that this is not new; but

What I claim as my invention, and desire to 40 secure by Letters Patent, is—

In a railroad-chair, the base-plate *a*, provided with ribs *B B* and legs *b b*, substantially as and for the purpose hereinbefore set forth.

Toronto, January 13, 1886.

PETER DE GUERRE.
